UNITED STATES PATENT OFFICE.

JAMES LATHROP, OF NORWICH, CONNECTICUT.

WEATHER-STRIP.

SPECIFICATION forming part of Letters Patent No. 394,864, dated December 18, 1888.

Application filed June 12, 1888. Serial No. 276,817. (No model.)

To all whom it may concern:

Be it known that I, JAMES LATHROP, a citizen of the United States, residing at Norwich, in the county of New London and State 5 of Connecticut, have invented certain new and useful Improvements in Weather-Strips, which improvements are fully set forth and described in the following specification, reference being had to the accompanying sheet 10 of drawings, in which—

Figure 1 is a perspective view of portions of a door and door-frame with a weather-strip embodying my improvements attached thereto, the door being shown as swung open 15 and the weather-strip or plate lying flat on the sill. Fig. 2 shows detached enlarged views (side and edge) of the lifter 5 and its fastening-staple 4'. Fig. 3 is a detached view of said staple.

20 This invention has for its object the improvement of that class of weather-strips described in Patent No. 56,209, issued July 10, 1866, to F. C. Gridley. In said class of strips certain objectionable results have been found 25 to exist in practice. The constant action of the free end of the sheet-metal lifter employed in such devices heretofore soon scrapes and digs out a hole in the engaging portion of the door and renders the weather-strip in- 30 operative. It also frequently occurs that the hinged plate that forms the weather-strip becomes clogged by ice or from other causes and refuses to lift when the door is closed, in which event the lifter is bent or broken 35 and rendered unfit for further use.

My purpose is to remedy these defects and to provide mechanism for lifting the weather-strip that will be as indestructible and as positive in action as the door itself.

40 In the drawings, the reference-figure 2 indicates the weather-strip proper, formed of sheet metal and hinged to the door-sill 3 by wire staples 4.

5 indicates my new form of lifter, made of stiff wire with one or more coils, 6, about 45 midway of its length. Said lifter is secured to the sill 3 at one end of plate 2 by the staple 4' in such position that one end of said lifter projects under the said plate. As a convenient means for rocking the lifter 5 to 50 cause it to raise the plate as the door is closed, I insert in said door a pin or screw, 7, said pin being so located that it engages the free end of the lifter as the door approaches its closed position, and thus rocks said lifter and 55 brings the plate up into engagement with the door to exclude all snow, rain, or cold air.

The described method of coiling the lifter-wire to make its hinge also provides a spring that yields to the pressure of pin 7 when the 60 plate becomes clogged and refuses to rise, and so prevents the breaking or bending of said lifter.

My improved device, as here described, is 65 of very simple construction, may be cheaply produced, and may be applied by any person of average intelligence without special instruction.

Having thus described my invention, I 70 claim—

In combination with a plate hinged to a door-sill, a door adapted to swing into engagement with said plate, having a projecting pin, 7, near its hinge side, as set forth, a wire lifter coiled to form a yielding hinge, 75 and a staple clamping said lifter-hinge to the sill, one arm of said lifter lying under the plate 2 and the other arm projecting upward into the path of pin 7, substantially as and for the objects specified.

JAMES LATHROP.
